GEAR PUMP

Géza Walter Müller, Bron, France, assignor to
 Societe Industrielle Generale de Mecanique
 Appliquee (S. I. G. M. A.), Venissieux (Depart-
 ment of Rhone), France, a society of France

Application March 8, 1946, Serial No. 652,896
 In France April 5, 1945

2 Claims. (Cl. 103—126)

1

The present invention has for its object improvements in gear pumps, and more particularly, although not exclusively, in pumps of this kind as are utilized for the manufacture of artificial textiles.

The chief object of my invention is to provide a pump of this kind which is better adapted to meet the requirements of practice than those used up to this time.

A preferred embodiment of the present invention will be hereinafter described with reference to the accompanying drawings, given merely by way of example, and in which:

Fig. 1 shows, in longitudinal section on the line I—I of Fig. 3, a pump made according to the invention;

Figs. 2, 3 and 4 are sections on the lines II—II, III—III and IV—IV of Fig. 1;

Fig. 5 is a view on an enlarged scale showing, in perspective, a portion of the pump element 20 visible on Fig. 4.

In the following description it will be supposed, by way of example, that the pump that is considered is a gear pump for viscous matters serving to the manufacture of artificial textiles such as, for instance, viscose, cellulose acetate, a cupro-textile, artificial wool, a synthetic textile material, etc.

Preferably, as shown the pump includes four juxtaposed pieces one of which constitutes the pump body 1, the second the plate 2 in which are provided the circular bores 3 for the housings of the pump gears 4a, 4b, the third a distance plate 5 and the fourth a closure plate 6. These four pieces are connected together by bolts 7 or analogous means.

A bore 1a in pump body 1 forms a bearing for control shaft 8 which carries, at one of its ends, pinion 4a keyed thereon by means of a lug 9. The other pinion 4b, in mesh with pinion 4a is mounted loose on a spindle 10 fixed to pump body 1.

The suction and discharge chambers provided in plate 2 on either side of the pair of gears are limited by oblique walls 11, 12.

The suction chamber limited by surface 11 is in communication with the suction conduit 13 of the pump.

The discharge chamber limited by oblique wall 12 leads to the discharge conduit system

2

which is constituted by the following elements:

(a) A longitudinal conduit 15a extending throughout plate 5;

(b) A transverse recess 15b provided in the front face of body 1;

(c) A second longitudinal conduit 15c, also provided in body 1, connected with conduit 15a by said recess 15b and extending parallel to the bearing 1a of control shaft 8;

(d) The inside of a U section ring 15d (for instance of synthetic rubber) acting also as packing member and pulsation damper; and

(e) A conduit 15e through which the fluid discharged by the pump flows out therefrom.

In order to obtain the desired lubrication of control shaft 8 over the whole length of its bearing 1a, the element 15c of the discharge system is placed in communication with the inside of said bearing through an elongated passage constituted by a slot 16 the longitudinal axis of which is parallel to said conduit element. Slot 16 extends the entire length of bearing 1a.

This construction ensures a self-lubrication of the control shaft, over the whole journaled surface thereof in the pump body, by means of the very fluid driven by the pump, and without danger of stagnation of any amount of said fluid inside the means which connect said conduit element with said shaft bearing.

Of course, the invention is not in any way limited to the embodiments above described.

What I claim is:

1. A gear pump which comprises, in combination, at least two gears, a pump body provided with a bore adapted to act as shaft bearing, and a shaft journaled in overhung fashion in said bearing carrying at one end one of said gears, said body being provided with passages forming a discharge conduit system for the fluid driven by said pump after its flow between said gears, said conduit system including a groove in said body parallel to said shaft bearing and close thereto through which the full delivery of the pump circulates, communicating with the inside 40 of said shaft bearing over the whole length of said bearing.

2. A gear pump which comprises, in combination, at least two gears, a pump body provided with a bore adapted to act as shaft bearing, and a shaft journaled in overhung fashion in said

bearing carrying at one end one of said gears, a cap carried by said body forming therewith a closed chamber at the other end of said shaft, and a packing ring against the inner face of said cap to prevent leakage between said cap and said shaft, said body being provided with passages forming a discharge conduit system for the fluid driven by said pump after its flow between said gears, said conduit system including a groove in said body parallel and close to said shaft bearing, opening into said chamber, through which the full delivery of the pump circulates communicating with the inside of said shaft bearing throughout the whole length of said bearing, and further including an outlet passage starting from said chamber and leading to the outside of the body.

GÉZA WALTER MÜLLER.
